UNITED STATES PATENT OFFICE

WILLIAM WHITNEY CHRISTMAS, OF NEW YORK, N. Y., ASSIGNOR, BY MESNE ASSIGNMENTS, TO THE GENERAL DEVELOPMENT COMPANY, OF HARTFORD, CONNECTICUT, A CORPORATION OF CONNECTICUT

FLYING WING

Application filed June 28, 1929. Serial No. 374,449.

My invention relates to the art of aviation and has for its object the production of an improved aeroplane for commercial and military use, having increased carrying capacity, speed, and safety factors over previously designed planes of its class.

I attain my object by employing what I may briefly designate as a flying wing, without any fuselage. The machine consists es-

10sentially of one continuous wing of sufficient dimensions to permit passengers, freight, and engines to be housed within it, framed on a double cruciform girder structure, having opposite trusses extending from tip to tip 15 and other parallel trusses extending fore and aft from points in advance of the leading edge to the tail group. The pilot's station or control room is in a pilot house attached at the middle of the leading edge of the 20 plane. Compartments or boots which may contain fuel or provide storage for other purposes are formed in the supports for the landing gears, which are located beneath the parallel fore and aft truss members of the 25 frame, and are directly connected to and built into the same. Each of these fore and aft trusses carries a power plant. Propulsion is by two or more propellers, each having a shaft journaled in said fore and aft trusses, 30 and these two trusses support the tail group comprising an elevator, a stabilizer and a plurality of rudders. The wing is shaped in a manner which will be described herein-after, and carries ailerons on its trailing edge 35 at opposite extremities.

Increased carrying capacity is attained by increasing the all over dimensions of the plane, whereby its vertical dimension or thickness is rendered sufficient to give storage 40 space and carrying space between the upper and lower members of the aerofoil. In other words, passengers, engines and freight are carried within the body of the wing, which may be upwards of 7 feet high with other dimensions proportionate thereto. Greater speed is attained not only by reducing the air resistance, but by increasing the available engine power. Greater safety is attained 45 because a monoplane of this type is very 50 stable and all parts including the weight car-

ried, are balanced. Owing to the increased size necessitated by the design, as well as the increased power, the machine can fly in any weather without danger of mishap and as all parts of the engines are immediately 55 available and within reach of the engineers at all times, the danger of forced landings due to engine trouble is practically eliminated.

My invention is illustrated in the accompanying drawings, in which

Fig. 1 is a plan view of my improved aero-plane;

Figs. 2 and 3 are respectively front and side elevations.

Referring to the drawings, A is the aerofoil or wing which is framed on an extended double cruciform cantilever truss having opposite members extending from one tip a to the other tip a' , and parallel fore and aft members extending from a point in advance of the leading edge to the tail group. The central portion a^2 of this wing has the leading edge and the trailing edge parallel or substantially so. The extended portions of the wing on the other hand, are preferably tapered as shown in Fig. 1, the front or entering edge being not only somewhat oblique but also rounded off at a^3 , while the rear or trailing edge is somewhat more 80 oblique with each aileron extended for approximately two-thirds of the distance from the tip to the base of the wing. It will be understood that these dimensions are arbitrary and may be varied without departing 85 from the invention. The two projecting wings a^4 — a^5 are so built and proportioned as to form a dihedral angle, with the central portion a^2 of the truss extending in a horizontal plane between them. Extending 90 fore and aft, parallel with each other, and crossing the wing spars or trusses, are the fore and aft trusses O—O'. The structure of these and of the main truss A will be presently described more in detail, but at this point it is only necessary to say that the fore and aft trusses are in box form and at 95 their rear ends carry the tail group T including stabilizer truss T', elevator E, and rudders R—R'—R². In order to prevent

100

warping, transverse strain or longitudinal vibration of these parts, a pair of diagonal cables C—C' are secured from points c—c' to a common point so as to stiffen the entire structure.

It is not intended in the present application, as it forms no direct part of the present invention, to describe the detailed mechanical structure of the main wing or aerofoil 10 and the fore and aft trusses. It should be stated however that both are built of assembled units of tubing or other material best suited to the purpose which may be for example chrome molybdenum steel, varying 15 in diameter from 3 to 5½ inches for the larger parts and down to ¾ inch for the smallest parts. These tubes are made in standard sections, are assembled by means of couplings to form a reticulated frame 20 uniform in every direction and cross braced diagonally of the truss in both horizontal and vertical planes.

The present design is not intended for small ships, the approximate dimensions of 25 one type of unit being for example as follows:

Span over all from tip a, to a' 230 feet.

Depth of chord, middle section a², is 53 feet.

30 Depth of chord wing tips a—a¹, 25 feet. Center section a², 40 feet by 53 feet.

The fore and aft trusses O—O' in box form, 7 feet by 7 feet, in widest section, tapering to 5 feet by 2½ feet at the tail 35 group, and 3 feet by 3 feet at each propeller.

Height of plane from ground to top of middle section a² (see Fig. 2) 28 feet.

40 Height of plane from ground to under-side of middle section a², 20 feet, 9 inches.

Height of plane at wing tips a—a' 35 feet.

The tail group T, with the exception of the stabilizer T', which is built and assembled similarly to the body of the aerofoil and 45 the fore and aft trusses, are of known or any suitable construction and are operated by controls worked in any suitable manner, as by means of a hand wheel w moving the elevator in its fore and aft motion, the ailerons 50 in its side motion, and the rudders in its rotary motion. The wheel w is located in the pilot's control station which may be located on the leading edge of the central section a² of the plane or within the same, 55 so that the pilot may have a clear view at all times.

A characteristic feature of this plane lies in the supports S—S' for the landing gear connected at L—L'. These supports S—S' 60 are of any suitable material, including metal and wood, forming boxes or tanks which from their dimensions and location are well adapted to carry quantities of fuel or other material to be transported. These supports 65 S—S' are parallel, and lie beneath the par-

allel fore and aft trusses O—O' in which the engines are carried, being built into the same and into the main wing trusses or spars so as to form part of the main cruciform structure and to carry the weight of the engines 70 directly when on the ground.

Between the two parallel trusses O—O' the central portion of the main wing a² is designed to house and carry passengers, freight, and supplies. The wing sections outside of the fore and aft trusses can also perform the same function. The motors are enclosed in the spaces within the fore and aft trusses where they cross the main wing spars or trusses. Two or more of these motors may 75 point forwardly and one or more may point to the rear, with a master gear between them meshing with pinions or gears on the respective motor shafts, which may be thrown into and out of engagement at will by the engineer. For this purpose any known or suitable form of clutch may be provided, or if desired, the gearing may be direct, the main shaft of each propeller extending back past the forward motor and being connected to the master gear, so that it may receive power 80 from 1, 2, 3 or more engines at will. In the machine described, the propellers have a diameter of 30 or more feet and operate at a 85 maximum speed of 400 R. P. M. or more.

The front or leading edge of the central section a² is provided with windows of non-shatterable glass in metal frames, as indicated at G in Figs. 1 and 2. The upper part of the entering edge is preferably solid, in common with the rest of the surface of the wing or aerofoil, which is adapted to resist all weather conditions, a suitable covering for this purpose being for example, veneered wood sheathing covered with stainless steel.

The vertical dimensions between the upper and lower surface of the central section a² of the wing being approximately 7 feet, 6 inches and the area of this central section being approximately 2100 square feet, there 100 is ample space and head room for the location of seats for upwards of 55 passengers, with rest rooms, dining room, smoking rooms, cabins, and other conveniences customary on 105 cruising ships. The glass windows G in their metal frames, afford a clear view at all times for the passengers and the weight is where it should be, to stabilize the plane.

The cruising speed of this machine is from 85 to 130 miles per hour, and its landing speed is approximately 41 miles per hour, the landing being rendered safe and easy by the large wing area and the relative close approach of the entire area to the earth, which produces air compression with consequent rapid deceleration.

What I claim is:-

1. An aeroplane of the type described, framed on a double cruciform girder structure composed of opposite truss members or 130

spars extending from tip to tip of the plane, and parallel fore and aft truss members each extending continuously without a break from a point in advance of the leading edge of the 5 plane to the tail group, each built directly and integrally into the structure of the wing trusses or spars, a power plant housed in the space within each of said fore and aft trusses, a propeller shaft therein driven by 10 each power plant, propellers supported on outboard bearings at the forward ends of said trusses, and a parallel pair of landing legs extending fore and aft beneath said fore and aft trusses, integrally connected therewith 15 and built thereinto, the main wing trusses or spars extending parallel to the ground and horizontally between the said parallel fore and aft trusses, and the projecting portions of the wing structure outside of said fore and 20 aft trusses inclining upwardly to form a dihedral angle, together with a skin secured over said framing to cover the outer surfaces of the aerofoil and of the fore and aft trusses, and diagonal bracing throughout the framing 25 and surfaces of the aerofoil, whereby all strains on component parts of the structure are transmitted and taken up uniformly by the cruciform frame and the braced surfaces and whereby in landing strains due thereto 30 are also uniformly distributed without concentrated strain on any particular part, while the main frame is relieved of all shock due to the masses of the power plants.

2. The aeroplane described in claim 1, with 35 the additional element of a pilot house hung in the space between the parallel fore and aft truss members so as to have clear vision between the same beneath the plane.

In testimony whereof I hereunto affix my 40 signature.

WILLIAM WHITNEY CHRISTMAS.
